PICNIC TABLE OR THE LIKE

Kenneth B. Godden, Cornell, Ill.

Application October 1, 1954, Serial No. 32,509

Term of patent 14 years

(Cl. D33—14)

Fig. 1

I claim:

The ornamental design for a picnic table or the like, substantially as shown.
